(57) **CLAIM**

The belted bow container top, as shown.

DESCRIPTION

FIG. 1 is a top to bottom perspective view of a belted bow container top showing my new design;
FIGS. 2, 3, 4 and 5 are side elevations at 90 degree offsets of a container top showing an embodiment of my new design;
FIG. 6 is a top view of a container top showing an embodiment of my new design; and,
FIG. 7 is a bottom view of a container top showing an embodiment of my new design.
The broken line showing is for illustrative purposes only, and
forms no part of the claimed design.
